UNITED STATES PATENT OFFICE.

THOMAS DANQUARD, OF NEW YORK, N. Y., ASSIGNOR TO AUTO PNEUMATIC ACTION CO.,
OF NEW YORK, N. Y., A CORPORATION OF NEW YORK.

DEVICE FOR ADJUSTING THE RELATION BETWEEN MUSIC-SHEET AND TRACKER.

1,187,975.

Specification of Letters Patent. Patented June 20, 1916.

Application filed January 20, 1910. Serial No. 539,108.

To all whom it may concern:

Be it known that I, THOMAS DANQUARD, a citizen of the United States, residing at New York, in the county of New York and 5 State of New York, have invented a new and useful Device for Adjusting the Relation Between Music-Sheets and Trackers, of which the following is a specification.

The object of this invention is to improve 10 on the structure shown in patent to O'Connor No. 789,053 dated May 2, 1905, for a web guiding device. In this patent is shown an automatic adjusting device for preserving the proper relation between the music 15 sheet and the tracker-bar, consisting of two orifices arranged in a spaced relation with the tracker, one of which is exposed when the sheet wanders to one side, and the other of which is exposed when the sheet wanders 20 to the other side. Pneumatic motors are controlled by these openings, and are so connected that when the sheet wanders in either direction one or the other of said motors will operate to restore the normal condition. 25

The object of the present invention is to improve said structure to obtain great accuracy of operation under all conditions.

Referring to the drawings and in detail, 30 Figure 1 is an elevation of a structure embodying part of my improvements; Fig. 2 is a plan view thereof; Fig. 3 is an end elevation of the adjusting mechanism for the roll; Fig. 4 is an elevation showing the construction employed when it is desired to adapt the device for different widths of paper; Fig. 5 is a cross-sectional view taken on the line 5—5 of Fig. 4; and Fig. 6 is a cross sectional view through the tracker. 35

Referring to the drawings and in detail 40 A designates the winding or drawing roll of a pneumatic action, and T and T' designates two trackers, the upper one T of which may be formed so as to operate with the usual eighty-eight note music, and the lower one T' to operate with the usual sixty-five note music. 45

10 designates a plunger or bearing which is mounted on a casing 11 which contains a 50 spring 12 bearing on the shoulder of the plunger 10. The plunger 10 is reduced in size, and extends out through the rear of the casing 11, and has an adjustable collar 13 thereon for limiting its right-hand movement. A shaft 14 having an enlarged and

slotted end is journaled in the framing, and in a suitable bracket in axial line with the plunger 10.

The roll R of music is snapped between the plunger 10 and the shaft 14 in the ordinary manner. A music sheet S is drawn therefrom and wound around the winding roll A. Between the two trackers T and T' I arrange control openings and pipes a and b. These are arranged so that when the music-sheet is in normal position the ends thereof will be just covered up, but so that if the music-sheet wanders in either direction one or the other of the openings will be uncovered. By arranging the openings between the two trackers, the same mechanism can be employed to keep the music sheet in normal position no matter whether the upper tracker T is employed with eighty-eight note music, or the lower tracker T' with sixty-five note music. 75

The pneumatic motors for adjusting the sheet are shown as arranged at the left of the winding roll. These motors are shown as consisting of oppositely arranged collapsible bellows M and M'. The flexible members of the bellows are connected together by a link 15, so that the motors will be connected and opposed. The motors are arranged on the sides of a valve box which 80 has a chamber 16 connecting with the exhaust of the instrument. The motor M is connected to said chamber 16, and to the atmosphere by passages controlled by an ordinary double valve 17, and the right-hand motor M' is similarly connected to the chamber 16 and to the atmosphere by passages controlled by a double valve 18. 85

The valve 17 is connected to a diaphragm 19 arranged over a chamber to which the pipe a is connected, and the right-hand valve 18 is connected to a diaphragm 20 arranged over a chamber to which the pipe b is connected. The usual leak or equalizing passages are arranged around said diaphragms. 100

The movable part of the right-hand motor M' is connected by a link 21 to a bell-crank lever 22 which connects by link 23 to an arm or lever 24 mounted on a shaft 25 journaled in suitable bearings on the frame. On 105 the other end of the shaft 25 is arranged an arm or lever 26 which connects by a link 27 to an arm 28 mounted on a shaft 29 journaled in a suitable bearing 30 secured to the frame. On the end of the shaft 29 is 110

arranged a cam 31, the inclined face of which bears on the end of the shaft 14. The shaft 29 is extended inside of the frame, and a handle 32 is secured thereon. In the normal position of the parts both motors M and M' are connected to the atmosphere.

If it is desired to adjust the music sheet on the trackers by hand the handle 32 is operated, which will turn the cam 31 and hence will adjust the shaft 14, and thereby the music roll R axially. As this adjustment takes place, the movable members of the motors M and M' will be slightly moved by the connections to the same, but however leaving the motors in position to act irrespective of the hand adjustment of the music roll. By this arrangement the music sheet can be accurately adjusted by hand to run properly on the tracker and to cover the openings a and b without interfering with the connections to the pneumatic motors, and without disturbing the operating connections therefrom which automatically adjust the music sheet in case the same wanders from normal position.

Suppose now that the music sheet in playing wanders to the right. This will uncover the opening a which will admit atmospheric pressure under the diaphragm 19, which will lift the left-hand double valve and connect the left-hand motor M with the suction chamber 16. This will operate the left-hand motor M, and will cause the connections from the motor to move in the direction indicated by the arrows, which will revolve the cam 31 in the direction shown in Fig. 3, which motion of the cam will move the shaft 14 and thereby the music roll R to the left, thereby moving the music sheet automatically back to normal position where the left-hand edge of the same covers the opening a. Since the opening a is covered, the left-hand double valve 17 will drop as the pressure on the diaphragm 19 will equalize through the small leak or bleeding passage around the same, and the parts will assume their normal position. If the music sheet wanders to the left, the right-hand opening b will be uncovered, and the right-hand motor M' will operate through the connections to move the music roll R to the right so as to bring the music sheet back to normal position. In this way the music sheet will be kept automatically in proper position, and notwithstanding this automatic adjustment, adjustment can be made by hand at any time without affecting the operative relation of the motors with the adjusting means.

It is often advisable to provide additional mechanism so that the automatic action previously described can take place, even if the music sheet expands or contracts and to obtain a very accurate operation, and to do this I provide a plurality of openings at each

side of the tracker-bar or tracker-bars, and

so arrange the valve mechanism that the same will operate with a music sheet which will cover both sets of openings, or with a music sheet which will only cover the inner set of openings, leaving both openings of the outer set uncovered. By this arrangement the two outer openings can be used for the normal width of sheet, and the two inner openings with a contracted sheet, or the two inner openings can be used for the normal sheet, and the two outer openings for expanded or swollen sheets. This arrangement is constructed as follows:—The motors M and M', valves 17 and 18, and passages a and b are arranged substantially as previously described, except the valve 17 is arranged to control the motor M', and the valve 18 the motor M, the pipes a and b being crossed for this purpose. The bell-crank lever 22 included in the connections between the motors, and the music roll is reversed in position as the motors are arranged to operate oppositely from the arrangement shown in Figs. 1 and 2. The valves 17 and 18 instead of communicating directly with the motors M and M' connect with passages, at the ends of which are arranged diaphragms 33, the inner surfaces of which are exposed to the exhaust in a chamber 34. The motors M and M' in this arrangement connect to said exhaust chamber 34 and to the atmosphere by passages controlled by double valves 35 and 36 which are actuated by said diaphragms 33. Additional openings and passages c and d are arranged on the trackers inside of the openings a and b. The passage c communicates with a chamber 37 over the valve 18, which chamber has a diaphragm 38 which is connected to the stem of said valve 18. The passage d connects to a chamber 39 over the valve 17, which chamber has a diaphragm 40 to which the stem of the valve 17 is connected. The diaphragms 38 and 40 are arranged in a chamber 41 which is connected to exhaust. The pipes a, b, c and d end in pneumatic control openings a', b', c', d'. The control openings a' and b' are spaced apart laterally of the note sheet a greater distance than the control openings c' and d'.

The operation is as follows: Suppose that a music sheet is employed wide enough to cover both sets of control openings a' and b' and c' and d'. Then the parts will assume the position shown in Fig. 4. If the music sheet now wanders to the right, control openings a' will be opened which will cause valve 17 to lift, and hence will allow atmospheric pressure on the left of the diaphragm 33 controlling the valve 35. The exhaust in the chamber 34 will therefore move the valve 35 to the right as shown in Fig. 5, and will connect said chamber 34 to the motor M'. This will move the music roll R to the left and will adjust the music-

sheet automatically to proper position to cover the control opening a' . If the music sheet wanders from normal position to the left, control opening b' will be uncovered, 5 and valves 18 and 36 will operate to connect motor M to the suction chamber 34, which will move the music sheet to the right and back to normal position. If a music sheet is employed which is not of a width 10 sufficient to cover the control openings a' and b' the same will operate through control openings c' and d' . Suppose a music sheet of this width be employed, and adjusted properly to normal position that is to cover 15 control openings c' and d' and uncover control openings a' and b' . The air pressure through control openings a' and b' will cause both valves 17 and 18 to lift which will cause valves 35 and 36 to move to the right, and 20 which will cause both motors M and M' to be subjected to the exhaust from chamber 34. But as both are exposed to exhaust and are connected together they will oppose and lock each other, and there will not be any 25 resultant movement of the motors. Now suppose the paper wanders to the right, so as to uncover control opening c' and cover up control opening b' . Since control opening c' is connected to the atmosphere, the 30 atmospheric pressure will be carried into the chamber 37, and will come on top of the diaphragm 38. The exhaust will therefore pull down valve 18, which will cause valve 36 to move to the left to let atmospheric pressure into the left-hand motor M. As this takes place the right-hand motor M' is still subjected to exhaust, because the valve 35 is still in its right-hand position, and this will cause the right-hand motor 40 M' to operate which will move the music roll R, and hence the sheet to the left until the same covers up the control opening c' . When the music sheet wanders to the right to uncover the control opening c' , the control opening b' is covered up by the right-hand edge of the sheet, but the downward movement of the valve 18 will not be opposed as there is a bleeding passage around each diaphragm 38 and 40 as shown in Fig. 45 5. When the music sheet is restored to normal position, as previously described, the control opening b' will be again uncovered, and the control opening c' covered which will cause the valve 18 to lift and the valve 36 to move to the right and lock the motors opposed to each other. The reverse action takes place when the music sheet wanders to the left uncovering the control opening d' and covering the control opening a' . By 55 this arrangement the music sheet will operate through the diaphragm 39, valve 17, valve 35 and motor M which will act to move the music sheet to the right back to normal position with its edge covering control opening d' when the valve 17 will lift

and the motors M and M' will again lock and oppose each other. The connections between the motors and the music roll are made to have considerable friction so that any slight overbalancing of one motor over 70 the other when both are subjected to exhaust will not cause any movement of the music roll. By this arrangement the music sheet will operate properly even if its width is such as to uncover normally control openings a' and b' , provided the same is still of a width to cover control openings c' and d' . By this arrangement provision can be made for the expansion of the sheets if openings c and d are spaced for the normal 75 width of music sheet, or provision may be made for contraction of the sheet, if control openings a' and b' are spaced for the normal width of music sheet.

The details shown and described may be 80 greatly varied by a skilled mechanic without departing from the scope of my invention as expressed in the claims.

Having thus fully described my invention, what I claim and desire to secure by 85 Letters Patent is:—

1. The combination of a tracker bar having a series of music apertures, a take-up roll for drawing a perforated note-sheet forward over the tracker bar, a spring-pressed plunger for receiving the left-hand shaft for receiving the right-hand end of a music roll, and an axially slideable shaft for receiving the right-hand end of a music roll, a pneumatic control opening, a 90 pneumatic motor arranged at the left of the tracker bar and connected to operate said axially movable shaft so that the music-roll will move axially against or, by the action of said spring, and connections 95 between said control opening and said pneumatic motor arranged so that the pneumatic motor will operate to maintain the normal lateral relation between the tracker bar and note-sheet.
2. The combination of a tracker bar having a series of music apertures, a take-up roll for drawing a perforated note-sheet forward over the tracker bar, a spring-pressed plunger for receiving the left-hand 100 end of a music roll, an axially movable shaft for receiving the right-hand end of a music roll, two pneumatic control openings, a pneumatic motor arranged at the left of the tracker bar and connected to operate 105 said axially movable shaft so that the music-roll will move axially against or, by the action of said spring, and connections 110 between said control openings and said pneumatic motor arranged so that the pneumatic motor will operate to maintain the normal lateral relation between the tracker bar and note-sheet.
3. The combination of a tracker bar having a series of music apertures, a take-up 115
- 120
- 125
- 130

- roll for drawing a perforated note-sheet forward over the tracker bar, a spring-pressed plunger for receiving the left-hand end of a music roll, an axially slidable shaft 5 for receiving the right-hand end of the music roll, a pneumatic control opening arranged so that the lateral deviation of the note-sheet will change its condition, a pneumatic motor arranged at the left of the 10 tracker bar, a cam for operating said slidable shaft, connections between said motor and said cam, and connections between said control opening and said pneumatic motor arranged so that the pneumatic motor will operate to maintain the 15 normal lateral relation between the tracker bar and note-sheet.
4. The combination of a tracker bar having a series of music apertures, a take-up roll 20 for drawing a perforated note-sheet forward over the tracker bar, a spring-pressed plunger for receiving the left-hand end of a music roll, an axially slidable shaft for receiving the right-hand end of a music roll, 25 a pneumatic control opening arranged so that the lateral deviation of the note-sheet will change its condition, a pneumatic motor arranged at the left of the tracker bar and connected to operate said axially slidable 30 shaft, a lever arranged in said connections so that the parts can be manually operated, and connections between said control opening and said pneumatic motor arranged so that the pneumatic motor will operate to 35 maintain the normal lateral relation between the tracker bar and note-sheet.
5. The combination of a tracker bar having a series of music apertures, means for drawing a perforated note-sheet forward 40 over the tracker bar, a pneumatic control opening for coöperation with the edge of the sheet, a second pneumatic control opening spaced a different distance from the music apertures relatively to the first 45 control opening and also arranged for coöperation with the same edge of the note sheet as the first named pneumatic control opening, a pneumatic motor connected to adjust the lateral relation between the note-sheet and tracker bar, and connections between said control openings and said pneumatic motor arranged so that the pneumatic motor will operate to maintain the normal 50 lateral relation between the tracker bar and note-sheets.
6. The combination of a tracker bar having a series of music apertures, means for drawing a perforated note-sheet forward over the tracker bar, a pneumatic control 60 opening carried by the tracker bar, a second pneumatic control opening carried by the tracker bar and arranged nearer to the music apertures than the first control opening and also arranged for coöperation with the same edge of the note sheet as the first 65

named pneumatic control opening, a pneumatic motor connected to adjust the lateral relation between the note-sheet and tracker bar, and connections between said control openings and said pneumatic motor arranged so that the pneumatic motor will operate to maintain the normal lateral relation between the tracker bar and note-sheets of different width. 70

7. The combination of a tracker bar having a series of music apertures, means for drawing a perforated note-sheet forward over the tracker bar, a set of two pneumatic control openings spaced a distance apart for coöperation with the edges of a note-sheet, 75 a second set of two pneumatic control openings spaced a different distance apart relatively to the first set, a pneumatic motor connected to adjust the lateral relation between the note-sheet and tracker bar, and 80 connections between said control openings and said pneumatic motor arranged so that the pneumatic motor will operate to maintain the normal lateral relation between the tracker bar and note-sheets. 85

8. The combination of a tracker bar having a series of music apertures, means for drawing a perforated note-sheet forward over the tracker bar, a set of two pneumatic control openings spaced a distance apart for coöperation with the edges of a note-sheet, 90 a second set of two pneumatic control openings spaced a narrower distance apart relatively to the first set for coöperation with the edges of a note-sheet of a less width, a pneumatic motor connected to adjust the lateral relation between the note-sheet and tracker bar, and connections between said control openings and said pneumatic motor arranged so that the pneumatic motor will 95 operate to maintain the normal lateral relation between the tracker bar and note-sheets of different width. 100

9. The combination of a tracker bar having a series of music apertures, means for drawing a perforated note-sheet forward over the tracker bar, a set of two pneumatic control openings spaced a distance apart for coöperation with the edges of a note-sheet, 110 a second set of two pneumatic control openings spaced a narrower distance apart relatively to the first set for coöperation with the edges of a note-sheet of a less width, a pneumatic motor connected to adjust the lateral relation between the note-sheet and 115 tracker bar, connections between the first set of pneumatic control openings and the motor arranged so that when one of said openings is uncovered the motor will operate, and so that when both of said openings are uncovered the motor will not operate, 120 and connections between the second set of guide openings and the motor arranged so that when both right-hand openings are uncovered the motor will work in one direc- 125 130

tion, and so that when both left-hand guide openings are uncovered the motor will operate in the opposite direction.

10. The combination of a tracker bar having a series of music apertures, means for drawing a perforated note-sheet forward over the tracker bar, a set of two pneumatic control openings spaced a distance apart for coöperation with the edges of a note-sheet, a second set of two pneumatic control openings spaced a narrower distance apart relatively to the first set for coöperation with the edges of a note-sheet of a less width, a pneumatic motor connected to adjust the lateral relation between the note-sheet and tracker bar, motor controlling valves controlled from said pneumatic control openings and arranged so that when either one of the first set of control openings is operative the motor will operate, so that if both of the said first set of control openings are simultaneously operative the motor will remain inoperative, and so that if either control opening of the second set is operative the motor will operate.

11. The combination of a tracker bar having a series of music apertures, means for drawing a perforated note-sheet forward, over the tracker bar, a set of two pneumatic control openings spaced a distance apart for coöperation with the edges of a note-sheet, a second set of two pneumatic control openings spaced a narrower distance apart relatively to the first set for coöperation with the edges of a note-sheet of a less width, a double pneumatic motor connected to adjust the lateral relation between the note-sheet and tracker bar, connections between said control openings and said pneumatic motor arranged so that when only one of the first set of control openings is operative one

part of the motor will work, so that when both of the first set of control openings are operative both parts of the motor will work in opposition and thereby balance each other, and so that when only one of the second set of control openings is operative one part of the motor will work, whereby the double motor will operate to maintain the normal lateral relation between the tracker bar and note-sheets of different width.

12. The combination of a tracker bar having a series of music apertures, means for drawing a perforated note-sheet forward over the tracker bar, a set of two pneumatic control openings spaced a distance apart for coöperation with the edges of a note-sheet, a second set of two pneumatic control openings spaced a narrower distance apart relatively to the first set for coöperation with the edges of a note-sheet of a less width, a double connected pneumatic motor arranged to adjust the lateral relation between the note-sheet and tracker bar, valves 35 and 36 for controlling the motors, valves 17 and 18 for controlling the valves 35 and 36, diaphragms for operating the valves 17 and 18 controlled by the first set of pneumatic control openings and diaphragms for operating the valves 17 and 18 controlled by the second set of pneumatic control openings, arranged so that the pneumatic motor will operate to maintain the normal lateral relation between the tracker bar and note-sheets of different width.

In testimony whereof I have hereunto set my hand, in the presence of two subscribing witnesses.

THOMAS DANQUARD.
